CLAIM

The ornamental design for a microphone, as shown and described.

DESCRIPTION

FIG. 1 is a left side view of a microphone showing my new design;

FIG. 2 is a front view thereof;

FIG. 3 is a top view thereof;

FIG. 4 is a right side view thereof;

FIG. 5 is a rear view thereof;

FIG. 6 is a bottom view thereof; and,

FIG. 7 is a perspective view thereof.

The microphone is shown with a symbolic break in its length. The appearance of any portion of the article between the break lines forms no part of the claimed design.

The broken lines show portions of the microphone that form no part of the claimed design.
